UNITED STATES PATENT OFFICE.

ABRAHAM LEVIN, OF MAPLE SHADE, NEW JERSEY.

DESIGN FOR A COMBINED TABLE LAMP AND SMOKER'S SET.

Application filed April 22, 1926. Serial No. 17,376. Term of patent 3½ years.

To all whom it may concern:

Be it known that I, ABRAHAM LEVIN, a citizen of the United States, residing at Maple Shade, in the county of Burlington and State of New Jersey, have invented a new, original, and ornamental Design for a Combined Table Lamp and Smoker's Set, of which the following is a specification, reference being had to the accompanying drawing, forming part thereof, and in which the figure is a perspective view of the combined table lamp and smoker's set.

I claim:

The ornamental design for a combined table lamp and smoker's set, as shown.

ABRAHAM LEVIN.
